UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

VACUUM TUBE.

Application filed April 20, 1921. Serial No. 462,916.

To all whom it may concern:

Be it known that I, WILLIAM G. HOUSKEEPER, a citizen of the United States, residing at New York, in the county of New York, State of New York, have invented certain new and useful Improvements in Vacuum Tubes, of which the following is a full, clear, concise, and exact description.

This invention relates to vacuum tubes and more especially to vacuum tubes of the audion type.

In my copending application Serial No. 396,014, filed July 13, 1920, is disclosed an audion in which the anode comprises a portion of the enclosing vessel, the cathode and grid being supported between insulating plates carried by a tubular member extending axially of the vessel and being enveloped by the cathode and grid of substantially cylindrical configuration. In certain instances it is desirable to remove the supporting member from its axial position in the tube because of the intense heat to which it is subjected in that position through radiation from the enclosing cathode.

It is the object of this invention to provide, in a tube of the above noted character, a structural arrangement whereby the means for maintaining the insulating plates in their spaced relation, is removed from the hot part of the tube and also whereby the spacing means is utilized as a current carrier. The object is accomplished by supporting one of the insulating plates from the stem of the enclosing vessel and supporting the second plate from the first plate by means of metal rods mounted in the first plate near the periphery thereof. Between the two plates are arranged a cathode and grid, the cathode being located between the supporting hooks and the rods acting as leads for supplying current to the cathode.

This invention will be better understood by having reference to the following specification and accompanying drawing wherein is shown a sectional view partly in elevation of a vacuum tube embodying the invention.

The vacuum tube comprises a cylindrical vessel 1 of metal, preferably copper, which is adapted to serve as one of the electrodes, preferably the anode. Electrical connection may be made to the anode 1 by simply fastening a wire, such as the wire 2, to the outside thereof. The anode is open at its lower end, which is flared out gradually at

3. The lower end of the anode is sealed to a base portion 4, preferably of glass, in which is provided a reentrant stem 5 having an outwardly extending tubular portion 6.

Arranged on the stem 5 is a collar 7, from which project supports 8 which are tied together at their upper ends by the cross member 9. Supported from the member 9 is a tubular metallic member 10 which extends through a plate 11 of insulating material, preferably lavite. Surrounding the member 10 and interposed between the plate 11 and the cross member 9 is a sleeve 12, by means of which the plate 11 is spaced from the member 9.

Mounted in the plate 11 near the periphery thereof are metal rods 13, preferably molybdenum, which are held in position by means of nuts 14. The upper ends of these rods are offset as shown at 15 and are attached to a second block of lavite 16 by means of nuts 17. Extending between the blocks 11 and 16 and arranged exterior of the rods 14 are wires 18 upon which is helically wrapped the conductor 19 constituting the grid electrode. The plate 11 is provided with six symmetrically arranged upwardly extending hooks and the plate 17 with four symmetrically disposed downwardly extending hooks 20. Interiorly of the rods 13, a two part 85 filamentary cathode 21 is strung between the hooks in such a manner as to assume a substantially cylindrical configuration, the ends of each part of the cathode being attached to the offset upper ends 15 of the rods 13. To the lower ends of the rods 13 are attached the lead wires 22 which are sealed in the stem 5 at the inner end thereof.

A lead wire 23 is provided for the grid electrode and is led out through the tubular member 6. The cathode is maintained under uniform tension by means of the springs 24 operating in conjunction with the lower hooks 20. This construction is described in detail and claimed in my United States 100 Patent No. 1,480,208 issued Jan. 8, 1924.

Supported from the plate 16 is an additional plate 25 which is of considerably larger diameter than the plate 16 and which serves as a spacing means to prevent the 105 electrode structure from approaching too closely the anode 1.

The above described structural arrangement locates the rods 13 for maintaining the insulating plates in their desired relation 110

outside of the hot part of the tube. Furthermore, the use of these rods as the current carrier for the cathode simplifies the manufacture of the tube.

5. What is claimed is:

1. An electron discharge device comprising an evacuated vessel having a stem, an insulating plate supported from said stem, rods mounted in said plate near the periphery thereof, a second insulating plate supported by said rods and a filamentary cathode strung between said plates, each end of said cathode being connected to one of said rods adjacent said second plate.
15. 2. An electron discharge device comprising an evacuated vessel having a stem, an insulating plate supported from said stem, rods mounted in said plate near the periphery thereof, a second insulating plate supported by said rods, a filamentary cathode strung between said plates, each end of said cathode being connected to one of said rods adjacent said plate and a control electrode surrounding said cathode and said rods.
25. 3. An electron discharge device comprising an evacuated vessel having a stem, an insulating plate supported from said stem, rods mounted in said plate, a second plate supported by said rods, a filamentary cathode

supported between said plates, each end of 30 said cathode being connected with one of said rods near one end thereof and lead wires connected with the other ends of said rods.

4. An electron discharge device comprising 35 an evacuated vessel having a stem, an insulating plate supported from said stem, rods mounted in said plate near the periphery thereof, said rods being offset inwardly 40 at their upper ends, a second insulating plate carried by said rods and a filamentary cathode strung between said plates interiorly of said rods, said cathode being substantially cylindrical in configuration and having its ends attached to the offset portions of said 45 rods.

5. An electron discharge device comprising 50 an evacuated vessel, an insulating plate supported in said vessel, rods mounted in said plate, a second insulating plate supported by said rods and a two part cathode supported between said plates, the ends of 55 each part of said cathode being connected to the upper ends of said rods.

In witness whereof, I hereunto subscribe 55 my name this 18th day of April A. D., 1921.

WILLIAM G. HOUSKEEPER.
